UNITED STATES PATENT OFFICE.

ALBERT G. HOTCHKISS, OF NEW YORK, N. Y.

AUTOMATIC LUBRICATING APPARATUS FOR FOIL-MILLS.

SPECIFICATION forming part of Letters Patent No. 425,795, dated April 15, 1890.

Application filed January 20, 1890. Serial No. 337,480. (No model.)

To all whom it may concern:

Be it known that I, ALBERT G. HOTCHKISS, a citizen of the United States, residing in the city and State of New York, have invented an improvement in Automatic Lubricating Apparatus for Foil-Mills, of which the following is a specification.

In the manufacture of tin and other metallic foil it is usual to make use of soap-water or similar lubricating material applied to the surfaces of the rolls between which the foil is passed, in order that the foil may not adhere to such rolls, and in some instances the lubricating-liquid has been applied to the roll or web of foil as it is passed into the machine.

The lubricating-liquid has usually been applied to the rolls by brushes in the hands of an attendant, and the operation is often imperfectly performed by the unskilled labor of boys.

By my present improvements both the rolls are kept lubricated in the most perfect and uniform manner automatically, thus rendering the operation of the foil-mill much more perfect, and at the same time lessening the expense, and I make use of a peculiarly-constructed holder for the roll of foil, so that the same can be supplied with lubricating material upon the surface of the foil previous to the same passing in between the rolls.

In the drawings, Figure 1 is an elevation, partially in section, one of the frames being removed, representing the automatic lubricating apparatus as applied to a foil-mill. Fig. 2 is a separate sectional plan view of the brush, and Fig. 3 is a diagram of the connections between the soap-water tank and the brushes.

The rolls A B are supported in the frames C C' and driven in any usual or desired manner. Usually gear-wheels are made use of, and the sheet or web of foil from the roll D passes in between the tension-bars 2 3 4, one of which is provided with disks at opposite edges of the sheet of foil to form guides.

The roll D for the foil is supported at its ends in the vertical holders E, the lower ends of which are received into the transverse trough-bed F upon a bracket F', extending out from the base C² of the frame C C', and there is a screw 6 passing through the lower ends of the holders E, whereby such holders

E can be adjusted transversely of the machine and within the trough-bed F, so that the roll of foil D may be presented at the proper place between the two rolls A B.

The water-trough G is made with sides 7 and a curved back 8 and with a downwardly-projecting spout 9, and it is of a size adapted to set beneath the roll of foil, so that the soap-water running regularly upon the foil from a pipe 10 will spread upon the surface of the foil, and the surplus soap-water will run down by the spout 9 into a receiving-tank beneath the rolls A B and can be used over again by pumping it up into the tank H.

The lubricating-brushes L M are each formed with a head 11, to which is connected a pipe N, with nozzles 12 passing in between the bristles of the brush, so as to constantly supply the lubricating-liquid through such pipes and nozzles to the surfaces of the rolls, and the liquid is spread with uniformity by the action of the bristles of the brushes, and in addition an end motion is given to such brush, as hereinafter set forth, so that the brush is made to act regularly and uniformly from end to end along the surface of the respective rolls. Each brush is provided with an arm 13, pivoted at one end to a stock P or P', and there is a spring 14 between the stock and the arm to press the brush toward the roll, and this spring yields to allow the brush to move away from the roll without being injured should the foil at any time wind around the roll itself. The upper stock P' is longer than the lower stock P, so as to extend up out of the way.

The stocks P P' are preferably slotted and held by the clamping-screws 15 to the head-pieces Q Q' upon the reciprocating bars R R', and these reciprocating bars are within bearings or boxes 16 upon the frames C C' of the machine, and there is a rocking lever S, pivoted at 17 and connected by links 18 to the ends of the respective reciprocating bars R R', and in this rocking lever is a slot 19 for the crank-pin 20 upon the revolving wheel T, to which a continuous revolution is given at the proper speed by any suitable power, and the crank-pin 20 is adjustable nearer to or farther from the center of the revolving wheel T, so as to give greater or less motion to the rocking lever S, in order to move the

lubricating-brushes longitudinally of the rolls to whatever extent is desired, and it will be noticed that these reciprocating brushes and the bars that hold the same are above and 5 below the foil as it passes in between the rolls, and hence they do not interfere with the foil and are not in the way of the workmen as they are attending to the introduction or removal of such foil, and the cross-bars Q² Q³ between the frames C C' serve as guides to the head-pieces Q Q' as they are reciprocated.

The soap-water tank H is preferably provided with a thermometer 21 and a glass tube 22 for indicating the level of the water in such 15 tank, and the discharge of the soap-water is regulated by the valve 25, and from this tank pipes H², either partially or wholly flexible, extend to the pipes N upon the brushes. I have represented these pipes H² as flexible 20 between the couplings 26 and the pipes N upon the respective brushes.

By this improvement the surfaces of the rolls A and B will be uniformly lubricated by the action of the reciprocating brushes and 25 soap-water or similar liquid, and the tension of the foil as it passes in between the rolls will be determined by the number of bars 2 3 4 around which the foil passes, as usual, and in consequence of the web or sheet of 30 foil being moistened uniformly with soap-water or similar lubricating material the tension-bars will be kept in the proper condition, so that they will not injure such foil.

I claim as my invention—

35 1. The combination, with the rolls in a foil-mill, of a reservoir or holder for soap-water or other lubricating-liquid, and brushes, and stocks for supporting such brushes in contact with the rolls, and pipes leading from the 40 reservoir to the brushes for supplying the lubricating material, substantially as set forth.

2. The combination, with the foil-rolls, of a brush, a head for the same, a reservoir or holder and a pipe for supplying lubricating-liquid to the brush, an arm attached to the 45 brush, a stock to which the arm is hinged, and a spring for pressing the brush toward the roll, substantially as set forth.

3. The combination, with the foil-rolls, of 50 brushes, a reservoir and pipes for supplying the lubricating-liquid to such brushes, bars and arms for supporting such brushes, and a rocking lever and crank for reciprocating the bars and brushes, substantially as set forth.

4. The combination, with the foil-rolls, of 55 the bars R R', the rocking lever S and links for connecting the same to the bars R R', a crank for giving motion to the rocking lever, brushes with lubricating material in contact with the respective foil-rolls, and yielding 60 arms connecting the brushes with the reciprocating bars, substantially as set forth.

5. The combination, with the foil-rolls and the frame for the same, of the bracket F', extending out from the base of the frame, the 65 transverse trough upon the said bracket, the vertical holders E and screw 6, for adjusting the holders, and a roll for the foil, substantially as set forth.

6. The combination, with the foil-roll, of the 70 water-trough G, adapted to set beneath and at the ends of such roll and provided with a spout for the lubricating material, and the foil-rolls and frame having a receiver for the lubricating material in the lower part of such 75 frame, substantially as set forth.

Signed by me this 10th day of January, 1890.

ALBERT G. HOTCHKISS.
